CLAIM

The ornamental design for a printing head for a printer of a computer, as shown and described.

DESCRIPTION

FIG. 1 is a top plan view of a printing head for a printer of a computer showing our new design; FIG. 2 is a front elevational view thereof; FIG. 3 is a right side elevational view thereof; FIG. 4 is a left side elevational view thereof; FIG. 5 is a rear elevational view thereof; FIG. 6 is a bottom plan view thereof; FIG. 7 is a front perspective view thereof; FIG. 8 is a rear perspective view thereof; and FIG. 9 is a reduced scale perspective view thereof showing its intended use.

The broken line representation of a printer in FIG. 9 is for illustrative purposes only and forms no part of the claimed design.

FIG. 2

FIG. 3

FIG. 5

FIG. 6

FIG. 4

FIG. 7

FIG. 8

FIG. 9
